C. B. Moore, Design for Clock Case.

N° 3042

Patented

MAY 12 1868

United States Patent Office.

GEORGE B. OWEN, OF WINSTED, CONNECTICUT.

Design No. 3,042, dated May 12, 1868.

DESIGN FOR A CLOCK-CASE.

The Schedule referred to in these Letters Patent and making part of the same.

TO ALL WHOM IT MAY CONCERN:

Be it known that I, GEORGE B. OWEN, of Winsted, in the county of Litchfield, and State of Connecticut, have invented a new and original Design for Clock-Case; and I do hereby declare that the following is a full, clear, and exact description thereof, which will enable those skilled in the art to make and use the same, reference being had to the accompanying drawings, forming part of this specification.

This invention relates to a new and original design for a clock-case front, of that class generally termed "Gothic."

In the accompanying sheet of drawings—

Figure 1 is a front view of a clock-case constructed according to my design.

Figure 2, a horizontal section of the same, taken in the line *x x*, fig. 1.

Similar letters of reference indicate corresponding parts.

A represents the base of the clock-case, which is of quadrilateral form, and has its upper edge, at the front and the ends, rounded in semicircular form, as shown at *a*.

The front of the body of the case, at each side, has a pilaster, *b*, of convex form in its horizontal section.

These pilasters are at or formed on the fronts of the sides *c* of the case, as shown in fig. 2, and the top of the case, which has a double pitch, or is of Gothic form, is rounded or made convex, as shown at *d d*, so as to correspond with *b b*, a pillar, *e*, with conical tips, *e*X, being on the top of each pilaster.

B is the door of the clock-case, the top of which is of Gothic form, to correspond with the top of the case.

Between the door *B* and the convex surfaces *b b*, *d d*, and the top of the base, *A*, there is a gilt moulding, *f*, the inner part of which, 1, is concave, and the other part, 2, a plane surface, as shown clearly in fig. 2.

I claim as new, and desire to secure by Letters Patent—

The configuration of the several parts, combined and arranged as shown and described, to form a new and original design for a clock-case.

GEO. B. OWEN.
